(57) **CLAIM**

The ornamental design for a bracelet as shown and described.

DESCRIPTION

FIG. 1 is a front perspective view of the bracelet;

FIG. 2 is a front view thereof;

FIG. 3 is rear view thereof;

FIG. 4 is a right-side thereof;

FIG. 5 is a left-side thereof;

FIG. 6 is top view thereof; and,

FIG. 7 is a bottom view thereof.

The broken lines immediately adjacent to the shaded areas represent portions of the bracelet and form no part of the claimed design. The other broken lines represent environmental subject matter only and form no part of the claimed design.

1 Claim, 6 Drawing Sheets
